(57) **CLAIM**

The ornamental design for an underwear absorbent liner as shown and described.

DESCRIPTION

FIG. 1 is a perspective view of an underwear absorbent liner, showing my new design.

FIG. 2 is a top view of the claimed design.

FIG. 3 is a bottom view of the claimed design.

FIG. 4 is a side view of the claimed design; and,

FIG. 5 is a front view of the claimed design.

1 Claim, 2 Drawing Sheets
